Geo. F. Kimmel
ATTORNEY.

UNITED STATES PATENT OFFICE.

PATRICK E. TABOR, OF JOPLIN, AND VOYLE V. KIRKPATRICK, OF JACKSON COUNTY, MISSOURI.

PUMP JACK.

Application filed May 14, 1923. Serial No. 639,000.

To all whom it may concern:

Be it known that we, PATRICK E. TABOR and VOYLE V. KIRKPATRICK, both citizens of the United States, said TABOR being a resident of Joplin, in the county of Jasper and State of Missouri, and said KIRKPATRICK being a resident of the county of Jackson and State of Missouri, have jointly invented new and useful Improvements in Pump Jacks, of which the following is a specification.

This invention relates to pump heads, and has for one of its objects to simplify and improve the construction and increase the efficiency and utility of devices of this character.

With these and other objects in view the invention consists of certain novel features of construction as hereinafter shown and described and then specifically pointed out in the claims, and in the drawings illustrative of the preferred embodiment of the invention.

Figure 1 is a side elevation.
25 Fig. 2 is a front elevation.

Fig. 3 is a vertical section on the line 3—3 of Fig. 2.

Fig. 4 is a section on the line 4—4 of Fig. 1.

30 The improved apparatus comprises a base portion 10 mounted on a suitable foundation 11, a supporting frame comprising upright standards 12 arranged in pairs and in spaced relation, each pair of standards being connected at their upper ends by inclined head members 13 and intermediate thereof by web members 14, and the web members connected by a transverse strut or brace 15.

The base member 10 is rigidly connected 40 to the foundation 11 as by stay bolts 16.

Mounted for rotation in bearings 17 in the inclined upper parts 13 of the frame, is a crank shaft having three cranks, two outer cranks 18 and 19 externally of the frame members 13 and extending in the same direction, and an intermediate crank 20 midway between the spaced frame members.

50 Mounted for oscillation in the spaced frame members at their highest point is a pivot shaft 21, and mounted on the ends of the pivot shaft externally of the frame members are rocker arms 22 and 23, while a like rocker arm 24 is mounted upon the same pivot shaft intermediate the frame members.

55 The rocker arms 22 and 23 are coupled

respectively with the cranks 18 and 19 by connecting rods 25 and 26, while the intermediate rocker arm 24 is coupled to the intermediate crank 20 by a connecting rod 27. Mounted on the crank shaft externally of the frame members 12 are gear wheels 28 and 29, and mounted through the frame members 12 near their rear sides is a main drive shaft 30 carrying pinions 31 and 32 engaging the gears 28 and 29. By this means the crank shaft will be actuated from the drive shaft through the pinions and gears, and the outer rocker arm vibrated in unison and the intermediate rocker arm vibrated alternately with the outer rocker arms. The outer cranks 18 are preferably provided with integral counter weights 33 and 34 as shown.

Attached at 35 to the base 10 is a combined guide member and support 36 having a rigid sleeve 37 forming the base portion of a packing device including a gland 38, the members 37 and 38 providing liquid tight guiding means for a tubular operating member, a portion of which is shown at 39.

At its outer end the member 36 is formed with a threaded step 40 to receive the lower end of a vertical guide rod 41. Attached at 42 and 43 to the inclined portions 13 of the frame sides are bracket devices 44 and 45, the latter coupled at their outer upper ends by a transverse tie member 46. The upper end 41 of the guide rod is connected to the tie member 46 as by a U-bolt 47, as shown.

Slidable on the guide rod 41 is a bracket 47 held in position by a cap 48, the bracket having lateral trunnions 49 and a downwardly directed socket to receive and support the upper end of a pump rod 50 which extends down through the tubular pump rod 39, as shown. The trunnions 49 constitute lower pivots to links 51 and 52 which are pivoted at their upper ends at 53 to the adjacent end of the rocker arm 24. By this arrangement the upward and downward movement of the rocker arm 24 will correspondingly move the pump rod 50.

Mounted to slide on the rod 41 is another bracket represented as a whole at 54 and held in movable position on the rod by a cap member 55, the bracket having a relatively large vertical aperture to receive a packing sleeve 56 in which the upper end of the tubular member 39 is secured as by threading, as shown in Fig. 3. The rod

50 operates through the sleeve 56, water tight by a packing gland 57.

The sleeve 56 is provided with trunnions 57 operating in half bearings in the bracket 54, to provide for a certain degree of rocking motion between the parts 54 and 56, to prevent cramping during the movements.

Extending laterally from the bracket 54 are arms 58-59, the arms having studs 60 and 61 respectively at their outer ends. A connecting rod 62 is mounted to swing at its lower end on the stud 60, and pivoted at the upper end at 63 to the rocker arm 22, while a similar connecting rod 64 is mounted to swing at its lower end on the stud 61 and pivoted at its upper end at 65 to the rocker arm 23.

The tubular member 39 and the rod 50 are adapted to be coupled to a pumping element, not shown, and when motion is applied to the drive shaft 40, the rocker arms 24 will be simultaneously vibrated to apply motion to the tubular pump rod, while the single rocker arm will apply motion to the single pump rod 50, and in alternation with the tubular pump rod. Thus two separate and independent motions will be alternately imparted to the rods to produce a continuous flow from the pumps to which the rods are attached.

The improved device is simple in construction, can be manufactured of any suitable material and of any required size and capacity.

The preferred embodiment of the invention is disclosed in the drawings and set forth in the specification, but it will be understood that modifications within the scope of the claims may be made in the construction without departing from the principle of the invention or sacrificing any of its advantages.

Having thus described the invention, what is claimed as new is:—

1. In an apparatus of the class described, a supporting frame including spaced side members, a shaft journalled on said frame

and formed with an intermediate crank disposed between the side members of the same and co-acting crank elements externally of the frame side members, an inner beam member mounted for oscillation between the frame side members, a connecting member between the intermediate crank and the inner beam member, co-acting outer beam members mounted for oscillation on the frame members externally thereof, connecting members respectively between the external elements and the outer beam members, co-acting pump rods, connecting means between the intermediate beam member and one of said pump rods, and connecting means between the external beam members and the other of said pump rods.

2. In an apparatus of the class described, a supporting frame including spaced side members, a shaft journalled on said frame and formed with an intermediate crank disposed between the side members of the same and co-acting crank elements externally of the frame side members, an inner beam member mounted for oscillation between the frame side members, a connecting member between the intermediate crank and the inner beam member, co-acting outer beam members mounted for oscillation on the frame members externally thereof, connecting members respectively between the external crank elements and the outer beam members, co-acting pump rods, a guide rod supported by said frame, a cross head element slidable on said guide rod and coupled to one of said pump rods, a bracket device slidable on said guide rod and coupled to the other pump rod, connecting means between the intermediate beam member and said bracket device, and connecting means between the external beam members and the cross head element.

In testimony whereof, we affix our signatures hereto.

PATRICK E. TABOR.
VOYLE V. KIRKPATRICK.
